UNITED STATES PATENT OFFICE

136,854

DESIGN FOR A HEADBAND ORNAMENT

Lena M. Julian, Brockton, Mass.

Application August 4, 1943, Serial No. 110,835

Term of patent 14 years

To all whom it may concern:

Be it known that I, Lena M. Julian, a citizen of the United States and a resident of Brockton, county of Plymouth, and State of Massachusetts, have invented a new, original, and ornamental Design for a Headband Ornament, of which the following is a specification, reference being made to the accompanying drawing forming part thereof.

In the drawing:

Fig. 1 is a perspective view of a headband ornament showing my new design in its fastened position; and

Fig. 2 is a perspective view thereof in its unfastened position.

I claim:

The ornamental design for a headband ornament, substantially as shown.

LENA M. JULIAN.
